UNITED STATES PATENT OFFICE.

MICHAEL F. CAREY, ISADORE ALTMAN, AND WINFIELD HENDRICKSON, OF PHILADELPHIA, PENNSYLVANIA.

DESIGN FOR A BICYCLE-LAMP.

SPECIFICATION forming part of Design No. 25,876, dated August 4, 1896.

Application filed June 25, 1896. Serial No. 596,945. Term of patent 7 years.

To all whom it may concern:

Be it known that we, MICHAEL F. CAREY, ISADORE ALTMAN, and WINFIELD HENDRICKSON, citizens of the United States, residing in the city and county of Philadelphia, State of Pennsylvania, have invented and produced a new and original Design for a Bicycle-Lamp, of which the following is a specification, reference being had to the accompanying drawing, forming part thereof.

The leading feature of our design for a bicycle or vehicle lamp is the configuration and ornamentation of the same, including a panel-sided body.

The figure represents a perspective view of a lamp embodying our design.

In the drawing, A designates the casing of

the lamp, the same consisting of the body B, the panels C on the sides thereof, and the cap D, the latter having a dome-shaped top 20 E, a flaring bottom E', and a bulging rim F intermediate of said bottom and top.

G designates the oil-reservoir, formed of the reversely-flaring bodies H and J, united by the rim K.

What we claim is—

The design for a lamp, substantially as described and shown.

MICHAEL F. CAREY.

ISADORE ALTMAN.

WINFIELD HENDRICKSON.
